(57) **CLAIM**

The ornamental design for a paint can rim lid, as shown and described.

DESCRIPTION

FIG. 1 is a top perspective view of a paint can rim lid showing my new design;

FIG. 2 is a front perspective view thereof;

FIG. 3 is a bottom perspective view thereof;

FIG. 4 is a rear plan view thereof; and,

FIG. 5 is a side plan view thereof, the opposite side being a mirror image thereof.

The broken lines in the drawings show the environment of the paint can rim lid that form no part of the claimed design.
